ELECTRIC DRILL

Burton P. Franklin, Bachelor's Hall, Va., and Samuel S. Leotta, Hatboro, Pa., assignors to H. K. Porter Company (Delaware), Danville, Va., a corporation of Delaware

Filed Jan. 2, 1962, Ser. No. 68,169

Term of patent 14 years

(Cl. D54—14)

FIG. 1

FIG. 3

FIG. 2

FIGURE 1 is a side elevation of an electric drill showing our new design;

FIGURE 2 is a top plan view of the electric drill; and FIGURE 3 is a front perspective view thereof.

The side of the drill not shown is a mirror image of the side shown in FIG. 1.

We claim:

The ornamental design for an electric drill, substantially as shown and described.
